UNITED STATES PATENT OFFICE

DAVID R. KNAPP, OF PHILADELPHIA, PENNSYLVANIA

MATERIAL-HANDLING APPARATUS

Application filed August 6, 1927. Serial No. 211,119.

The present invention relates to material handling apparatus and more particularly to the loading of material at one place, transporting it to and unloading it at another place. By way of example, the apparatus of the present invention is shown and described as handling coal in mining operations, but the invention is not limited to this particular material.

10 In the mining of coal it is the general practice to work from a main entry, large enough to accommodate the ordinary mine cars, into lateral passages or rooms which correspond generally to the height of the coal vein and 15 when such veins are thick different classes of shovels are used to load the broken coal into cars or deposit it upon conveyor belts to be transported to the loading point. Where veins are thin, say from two to four feet in 20 thickness, a very different and difficult problem is presented because of the lack of head room for shovels, mine cars and other equipment. Head room can be obtained for this equipment by removing the top or bottom 25 slate between which the coal lies, but this is expensive work because besides being removed to make the necessary head room it has to be transported out of the mine and deposited on refuse banks. To overcome this, 30 mechanical means have to be resorted to to remove the coal from the working face and deposit it in cars located in the main entry and the means now employed are rope operated scrapers requiring a number of men to 35 each scraper and great loss of time in preparing for operation. This is because props, pulleys, and various auxiliary equipment must be set up before the rope operated scrapers are ready for use. These scrapers are 40 usually operated from a double drum hoist permanently mounted in the main entry for the side rooms or laterals and are several hundred feet from the loading point of the scrapers. In consequence the hoist operator has 45 to depend upon bell signals and since he cannot see the scrapers in operation it is quite a common occurrence for a scraper to foul a jack prop or a pulley causing roof breaks and slides which endanger the loaders in the

laterals, loss of time in repairs, and consequent decrease in production.

Some of the objects of the present invention are to provide a material handling apparatus which overcomes the foregoing disadvantages; to provide an apparatus which can be operated and controlled by one man in place of five or six; to provide an apparatus whereby production is increased many times over present day methods; to provide an automatic loader for removing material from one place to another; to provide a loading apparatus for operation in thin veins or where head room is limited as well as in thick coal veins; to provide a self-propelled material 60 loader whereby loose and partly loose material is broken up, automatically loaded and transported to a discharge point and reloaded on cars; to provide a material handling apparatus which does not require the use or setting up of props, or other special equipment 65 in the place of use; and to provide other improvements as will hereinafter appear.

In the accompanying drawings, Fig. 1 shown in the upper part of Sheets 1 and 2 75 represents a side elevation of a material loader embodying one form of the present invention; Fig. 2 shown on Sheets 3 and 4 represents a plan of the same; Fig. 3 shown on the lower part of Sheets 1 and 2 represents a side elevation of the loader with the 80 drum in section; Fig. 4 represents a section on line 4-4 of Fig. 1; Fig. 5 represents a front elevation of the loader; Fig. 6 represents a plan of a mine layout showing the 85 apparatus of the present invention and its control adjuncts; Fig. 7 represents a section in elevation through an entry and coal vein with the apparatus positioned for unloading; and Fig. 8 represents a detail in end elevation.

Referring to the drawings, one form of the present invention consists of a cylindrical drum 10, of any desired diameter and length to give the required results, is arranged to 95 be propelled in the direction of the pile of material to be moved and at the same time to have a rotating motion for collecting purposes. The end of this drum 10 which is to be worked into the material is preferably 100

formed by cutting it on a plane inclined to the axis of the drum 10, and one portion of the edge of the drum so formed is provided with cutting teeth 11, here designated for convenience "l" to "n". It will be evident as the drum is rotated and advanced into a pile of material that a portion only of the edge acts to cut into and break up the material, and hence that portion only is provided with the aforesaid breaking or cutting teeth 11. The opposite or discharge end of the drum 10 is closed by a fixed semi-circular segment plate 12, while the opposite semi-circular portion of the drum end is closed by a movable semi-circular segment door 13 which is preferably hinged to the fixed plate 12 and provided with locking fastenings 14 whereby it can be unlocked and raised to open position where it is fastened temporarily while the contents of the drum are being discharged.

For the purpose of feeding the material into the drum 10 and thus causing the latter to be filled so that the material can be transported to another location, there is provided internally of the drum 10 a helical feed flange or screw 15, the outer periphery of which is rigidly fastened to the internal wall of the drum 10 while the depth of the flange 15 varies throughout the length of the drum. This varying depth of the feed flange or screw 15 is so arranged in order to provide a relatively small axial receiving opening at the working end of the drum 10 and which gradually increases as the depth of the flange 15 decreases toward the discharge end of the drum 10. Preferably the pitch of the flange or screw 15 is the same as the diameter of the drum and hence between each convolution of the spiral there is a chamber of sufficient size to hold a considerable quantity of the material being fed.

As a means for mounting the drum 10 for rotation about its axis and also for imparting the desired rotary motion to it, a pair of arc shaped saddles 16 are provided and spaced apart axially of the drum a proper distance to support the drum for efficient distribution of its weight. These saddles 16 each consist of a body, such as a casting, provided with suitably located bearing slots 17 which journal the hub bearings of supporting rollers 18 upon which the drum is mounted. Each of these saddles 16 is also provided with a pair of cap bearings 20, which are arranged to be bolted in position after the drum has been mounted in the saddles, and these cap bearings are spaced respectively at opposite sides of the drum and carry rollers 21 in frictional contact with the upper half 66 of the drum 10 in order that the latter cannot force its way out of the supporting or base saddles 16. It will thus be evident that the drum 10, when mounted in the saddle 16, is not only supported in a stable and positive manner, but is also free to rotate rela-

tive to the saddles and with little friction. Also, when so assembled with the cap bearings 20 bolted in place, it is prevented from being forced out of the saddles and freely held for rotation about a fixed axis. It should be noted that the friction guide rollers 18 and 21 of each set lie in the same plane and between ring collars 19 fast to the drum 10 and in this way end thrust of the drum is taken care of. In the present instance, rotary motion is transmitted to the drum 10 by the provision of a gear 22 fast to the outside of the drum 10 and in a location to effectively transmit the necessary torque for the purpose intended. A toothed drive chain 23 encircles the drum 10 in mesh with the gear 22 and also passes about a pinion 24 fast to the shaft 25 of an electric motor 26 which is carried by a suitably fixed part.

For the purpose of mounting the saddles 16 so that the drum can be moved in the direction of its axis either toward a pile of material or away therefrom to transport the material to a loading place, each saddle 16 has oppositely projecting bed plates 27 which are respectively bolted, riveted or otherwise made fast to a pair of channel bars 28. These bars 28 extend lengthwise of the drum in parallel relation and each terminates at its ends in bifurcated heads 30 which respectively straddle sprockets 31 and are provided with bottom slots 32 which respectively receive the journal boxes 33 or bearings of the respective sprockets 31. The two aligned sprockets at one side of the drum carry a tractor belt or chain 34 and the two sprockets 31 at the opposite side of the drum also carry a tractor chain or belt 35. At intermediate points throughout the length of both channel bars 28 there are rotatively mounted toothed rollers 36 for guiding and meshing with the tractor chains 34 and 35. Thus in the preferred form of the invention, the side channels 28, the sprockets 31, the chains 34 and 35, and the toothed rollers 36 form a tractor of the caterpillar type, which when operating serves to propel the carriage of which the saddles are a part and thus advance the drum either forwardly or rearwardly.

In order to transmit power to propel the endless tractor belts 34 and 35, one pair of the sprockets 31, here shown as the rear pair, is arranged to be driven by sprocket chains 37 respectively encircling driven sprockets 38 fixed to the sprockets 31 and sprocket wheels 40 respectively fixed to the driving shafts 41 of a pair of motors 42. These motors 42 are anchored to the respective channel bars 28 at opposite sides of the drum 10 and located in relatively close proximity to the rear sprockets 31 to which each transmits power. Thus the two motors operate by suitable control in or out of synchronism depending upon the motion desired and each

is of course capable of reversal so that the sprockets 31 can be driven either forwardly or rearwardly.

Since it is desirable to maintain the path of movement of the tractor belts 34 and 35 clear of constructions, the forward ends of the two channel bars 28 carry forwardly projecting aprons 43 which have an upwardly flared scooping edge 44, the function of which is to ride in close relation to the floor or ground and push any loose material or obstructions out of the way and direct it toward the front or path of the drum 10. It will also be noted that these aprons 43 have a substantially vertical shield part 45 which is shaped at one side to conform to the contour of the drum and thus prevent material from working along the sides of the drum. Also at the rear end of the carriage there are inclined scoop members 46 located respectively in alignment with the tractor belts 34 and 35 to clear the paths for the tractor feet when the apparatus is driven rearwardly.

For the purpose of supplying current to the several motors upon the carriage of the drum 10, a cable 47 carrying the motor current lead wires is led from the rear of the machine and passes about pulleys 48 located where necessary and terminates in a winding drum 50. This drum 50 is fast upon a shaft 51 which has keyed thereon a gear 52 in mesh with a pinion 53 keyed to a shaft 49 of a constant torque single direction motor 54. The lead or conductor wires of the cable 47 terminate respectively in electrical bond with conducting collecting rings 55 and 56 which are mounted respectively upon discs 57 on the drum 50. These collecting rings 56 rotate in contact with collecting brushes 58 mounted in insulated relation upon a base 60, and one brush leads to the positive source of current and the opposite brush to the negative source of current. The motor 54 receives its current by way of conductors 61 and 62 leading to the same source of current supply but in one of the leads to the motor 54 there is a fixed resistance 63 so that the full torque is maintained constant for cable take-up. In other words, the introduction of the resistance into the circuit of the motor 54 allows this motor to maintain sufficient torque to always take up the slack of the cable 47 but insufficient torque to hamper the operation of the driving motors 42. In Fig. 6 a somewhat diagrammatic mine layout is shown with the takeup motor and its adjuncts located in a side pocket or recess 64 opening off of the main entry 65 through which the loading cars travel and thus it is out of the path of any of the movable equipment and the cable 47 can be swung in any direction depending upon where the automatic loader is working while a three-way pulley set 66 at the mouth of the pocket 64 provides for

changing the direction of the cable 47 as desired.

The operation of the apparatus can be followed from Figs. 6 and 7 wherein the main car loading entry 65 is shown with side laterals 70 or passages 67 opening into it from a level substantially even with the tops of the cars to be loaded. As customary, the passages 67 communicate with each other between piers or walls 68 which latter serve to shore the ceilings and prevent collapse as the veins are worked. After the passages 67 are fully worked, the material of the piers 68 is taken out in the usual practice. When removing the coal from a passage 67, a blast is used to throw down a mass of coal at the end of the passage and the operator of the self loading and transferring machine starts the motors 42 to advance the machine into the passage. At this time the discharge door 13 is closed and locked 85 so that the entering material collects within and fills the drum 10. When the inclined cutting and breaking edge of the drum 10 reaches the mass of material, the operator starts the motor 26 so that the drum begins to rotate 90 at its constant speed and the portion of edge having the teeth 11 bites into the mass gradually increasing the depth of the bite until the maximum length of the projecting edge reaches the floor of the passage. This ends the 95 cutting or breaking up action of the edge for one revolution and brings the mouth edge of the helical flange to its scooping or initial material receiving position. On the remaining portion therefore, of this revolution, the forward and rotary movement of the drum feeds the material into the space between the first two convolutions of the helical flange 15. At the completion of the partial revolution the most advanced point of the edge 11 or 105 tooth "n" is again at the top of the drum while tooth "l" is again taking hold of the material and is followed successively by the other teeth until tooth "n" is turned away from the material again. Meanwhile the material in the first chamber of the drum has automatically been fed into the next chamber and a new quantity takes its place in the first chamber. Thus rotation of the drum 10 with constant forward feed results in the drum 110 finally being filled to capacity, and when this occurs the operator reverses the motors 42 and backs the machine out of the passage until its discharge end is over the car to be filled. During this backing out of the machine, the torque of the motor 54 takes up the slack of the cable 47, maintains it under tension, and avoids fouling of cable and pulleys. With the machine in position to discharge, the propelling motors 42 are stopped, the discharge door 13 opened and bolted in open position and the motor 26 continued in operation. As a result the material is fed to the rear or discharge end and during one-half revolution the open half of the discharge end is 130

down to allow the material to fall into the car and on the other half revolution the material is being fed into this end chamber of the helical feed screw.

5 While the mechanism of the present invention is shown in its preferred form mounted upon a caterpillar tractor, it will be understood any suitable vehicle can be used for supporting and moving the drum and its 10 parts. Thus, for example, when rock and other material is to be removed in the forming of the car entries and the drum must necessarily work on the same level with the material removing cars, the drum and its associated parts can be mounted on a truck in an inclined position so that its cutting edge travels close to the floor level while its discharging end is raised above the line of the car. In this way rock or other material which 15 20 has been blown down by blasting can be fed upwardly on an incline and discharged directly into the waiting car in position at the rear.

While only a single form is shown in which this invention may be embodied, it is to be understood that the invention is not limited to any specific construction, but might be applied to various forms without departing from the spirit of the invention or the scope of the appended claims.

30 Having thus described my invention, I claim:

1. A material handling apparatus comprising a vehicle, a drum mounted on said vehicle for rotary movement, said drum being closed at one end and open at the other end, a control door for the closed end of said drum, the open end of said drum being provided with cutting teeth, a helical member fixed within said drum, and means to rotate said drum.

40 2. A material handling apparatus comprising a vehicle, a drum mounted on said vehicle for rotary movement, said drum being closed at one end and open at the other end, a control door for the closed end of said drum, the open end of said drum being provided with cutting teeth, a helical member fixed within said drum, means to rotate said drum, and means to advance said vehicle while said drum is rotating.

50 3. A material handling apparatus comprising a vehicle, a drum mounted on said vehicle for rotary movement and having one end bevelled to provide a cutting edge, teeth on a portion of said edge, a helical member mounted in said drum, means to rotate said drum, and means to move said toothed edge into a mass of material while said drum rotates.

60 4. A material handling apparatus comprising a vehicle, a drum mounted on said vehicle for rotary movement and having one end bevelled to provide a cutting edge, teeth on a portion of said edge, a helical member mounted in said drum forming a through passage of gradually increasing diameter, means

to rotate said drum, and means to move said toothed edge into a mass of material while said drum rotates.

5. A material handling apparatus comprising a vehicle, a drum mounted on said vehicle for rotary movement and having one end bevelled to provide a cutting edge, a helical member forming a through passage of gradually increasing diameter mounted in said drum, means to rotate said drum, and means to move said vehicle towards and away from a mass of material.

6. A material handling apparatus comprising a vehicle, a drum mounted on said vehicle for rotary movement, a plurality of cutting teeth on a portion of one end edge of said drum and arranged to successively increase the depth of a cut as said drum rotates, a helical feed member in said drum, and means to rotate said drum.

7. A material handling apparatus comprising a vehicle, a drum mounted on said vehicle for rotary movement, a plurality of cutting teeth on a portion of one end edge of said drum and arranged to successively increase the depth of a cut as said drum rotates, a helical feed member in said drum having one end convolution starting in close proximity to the end tooth of the series of teeth, and means to rotate said drum.

8. A material handling apparatus comprising a vehicle, a drum mounted on said vehicle for rotary movement, said drum being closed at one end and open at the other end, a control door for the closed end of said drum, the open end of said drum being formed with a cutting edge, a helical member fixed within said drum, and means to rotate said drum.

Signed at Philadelphia, county of Philadelphia, State of Pennsylvania, this 4th day of August, 1927.
